THERMOCHROMIC THERMOMETER

Philip L. Van Kersen, P.O. Box 40423,
Indianapolis, Ind. 46240

Filed Nov. 12, 1973, Ser. No. 414,744

Term of patent 14 years

Int. Cl. D10—04

U.S. Cl. D10—57

Fig. 1

Fig. 3

Fig. 2

Fig. 4

FIG. 1 is a front elevational view of a thermochromic thermometer showing my new design;

FIG. 2 is a rear elevational view thereof;

FIG. 3 is a typical side elevational view thereof;

FIG. 4 is a front elevational view of another embodiment of my new design of FIG. 1, the rear and sides being identical therewith.

I claim:

The ornamental design for a thermochromic thermometer, as shown and described.
